JUG

James R. McCollum, Downey, Calif., assignor to Thatcher Glass Manufacturing Company, Inc., New York, N.Y., a corporation of New York

Filed Mar. 22, 1961, Ser. No. 64,432

Term of patent 14 years

(Cl. D58—5)

FIGURE 1 is a side elevational view of a jug showing my design;

FIGURE 2 is an elevational view of the same jug as seen from the right of FIGURE 1;

FIGURE 3 is a top plan view of the jug;

FIGURE 4 is a cross-sectional view of the jug taken on the line 4—4 of FIGURE 1;

The dominant features of my design reside in the portions shown in full lines.

I claim:

The ornamental design for a jug, substantially as shown and described.
